UNITED STATES PATENT OFFICE.

ARTHUR R. BAKER, OF INDIANAPOLIS, INDIANA, ASSIGNOR, BY MESNE ASSIGNMENTS, TO CHARLES G. McCUTCHEON, OF INDIANAPOLIS, INDIANA.

MOUNTING FOR MAGNETO IGNITERS.

Application filed October 30, 1919. Serial No. 334,443.

To all whom it may concern:

Be it known that I, ARTHUR R. BAKER, a citizen of the United States, residing at Indianapolis, in the county of Marion and State of Indiana, have invented new and useful Mountings for Magneto Igniters, of which the following is a specification.

It is the object of my invention to improve the mounting of the igniter contacts and the oscillating ignition magneto of an internal combustion engine, more particularly in connection with the type of mounting shown in my prior Patent No. 1,306,134, granted June 10, 1919; to make it possible to make the supporting arms for the magneto of steel or other strong and malleable metal while making the supporting plug for igniter contacts of cast iron, whereby greater strength and freedom from breakage may be secured for the former while the qualities of cast iron may be obtained for the heat-exposed igniter plug in which the fixed and especially the movable igniter contacts are mounted; to insure the proper relative positioning of the two parts of the mounting when they are together, and especially when they are in place on the engine; to make it possible to cast the plug carrying the igniter contacts with its flange horizontal whereby blow holes which are otherwise found frequently to develop are avoided; to lessen the expense of maintenance, by making possible the replacement of one part of the mounting in case it fails without requiring that a complete new mounting be provided.

The accompanying drawing illustrates my invention: Fig. 1 is a perspective view of my improved two-part bracket, and the igniter contacts associated therewith, indicating the associated magneto in dotted lines; Fig. 2 is a horizontal section through the bracket, looking from the bottom, showing the igniter contacts, but with the associated magneto omitted and with its supporting arms partly broken away; Fig. 3 is a front elevation of the igniter plug and the associated igniter contacts, with the magneto-supporting part removed; Fig. 4 is a perspective view of the magneto-supporting part alone; and Fig. 5 is a perspective view similar to Fig. 4, but showing a modification in which the magneto is supported on a shelf.

My improved bracket comprises two parts 55 A and B, for carrying the igniter contacts and the magneto respectively. The part A is preferably made of cast iron, while the part B is of some strong malleable metal, such as a casting or stamping of steel or manganese bronze.

The part A, or igniter-plug part, comprises a bolt flange 10 with the usual bolt ears, from one face of which flange usually projects a plug 11 which extends into the 65 engine cylinder and carries the fixed and movable igniter contacts 12 and 13. The fixed contact is suitably connected by a wire 14 to one terminal of the magneto, (the other terminal usually being grounded,) 70 such wire conveniently passing through a suitable hole in the flange 10 as is clear from Fig. 3. The flange 10 is also preferably provided on the opposite face from the plug 11 with a central boss 15, though 75 this is not essential. The details of the igniter contacts are also not essential to the present invention. This part A is preferably made of cast iron, and may be cast with the flange 10 horizontal and the plug 80 11 downward; this eliminates certain blow holes which are found frequently to occur when the plug is cast with the flange in a vertical position as is necessary in the one-piece bracket shown in my aforesaid patent. It is desirable to have the part A of 85 cast iron, both because of the heat to which it is subjected and because of the better bearing qualities of cast iron than steel in the bearing surfaces on which the steel 90 shaft of the movable igniter contact 13 moves.

The part B has a central supporting flange from which projects a magneto-supporting portion. In the preferred form of 95 my invention such portion comprises two projecting arms 21 and 22 on which the oscillating magneto 23 and its returning springs 24 are mounted in the same manner as they are mounted in the construction 100 set forth in my aforesaid Patent No. 1,306,134; this form is shown in Figs. 1 to 4. In the modification shown in Fig. 5 the magneto-supporting portion in a shelf 30, on which the magneto rests. The flange 20 105 in either case is provided with a central opening 25 which loosely receives the boss 15; but the fit of such boss in such hole is

2
 preferably very loose so that no positioning is obtained by it. In order to obtain the proper relative positioning of the parts A and B, each of the two bolt ears of the flange 10 of the part A has pressed into it a tube or bushing 26, preferably of steel; this tube or bushing receives the studs or bolts 27 by which the whole device is attached to the engine. The tubes 26 project outward beyond the outer face of the flange 10, and the flange 20 is provided with holes 28 which register with and fit over the projecting ends of the tubes 26 when the two parts A and B are put together as shown in Figs. 1 and 2. The fit of the tubes 26 in the bolt ears of one flange—shown as the flange 10—is preferably a tight press fit. The fit of the tubes 26 in the other flange—shown as the flange 20—provides just enough clearance to prevent binding of the two parts, so that by the tubes 26 and holes 28 the two parts A and B are held in proper relative position when they are put together. This clearance is greatly exaggerated in Fig. 2, in order to show that the tubes 26 are tight in the other flange, for such clearance is ordinarily but two or three thousandths of an inch, which is too small to show on the drawing. The projecting portions of the tube 26 which project into the holes 28 are preferably slightly shorter than the thickness of the flange 20, so that the heads of the bolts or the nuts on the studs 27 by which the device is attached to the engine will bear against the face of the flange 20 and clamp the flanges 20 and 10 together and the flange 10 against the engine cylinder 29.

By removing these nuts or bolts, the part B may be removed alone, or both parts A and B may be removed. In case of breakage or wear of either part a new part may be substituted for the broken or worn part without requiring a new part for the other. Usually it is the part A which will wear out, and a new part A may be carried in stock at small expense. When the two parts are put back on the engine, their proper relative positioning is insured by the fit of the tubes 26 in the holes 28. This same fit permits the two parts to be put together in proper relation at a workman's bench to permit their relative adjustment when it is necessary; this may be done without bolts, for the proper relative positioning of the two parts is not dependent on the bolts.

I claim as my invention:

1. A supporting bracket for oscillating magnetos and igniter contacts, comprising an igniter-plug part for carrying the igniter contacts, and a magneto-supporting part arranged to bear against the igniter-plug part, said two parts having registering bolt holes so that the same studs or bolts may be used for attaching both parts to the engine, one part being provided with tubular projections which fit into the bolt holes of the other part and through which the attaching studs or bolts project.

2. A supporting bracket for oscillating magnetos and igniter contacts, comprising an igniter-plug part for carrying the igniter contacts, and a magneto-supporting part arranged to bear against the igniter-plug part, said two parts having registering bolt holes so that the same studs or bolts may be used for attaching both parts to the engine, said parts being provided with interfitting projections and openings for positioning the two parts relatively to each other.

3. A supporting bracket for oscillating magnetos and igniter contacts, comprising an igniter-plug part for carrying the igniter contacts, and a magneto-supporting part arranged to bear against the igniter-plug part, said two parts having registering bolt holes so that the same studs or bolts may be used for attaching both parts to the engine, said parts being provided with interfitting projections and openings for positioning the two parts relatively to each other independently of bolts or studs in such holes.

4. A supporting bracket for oscillating magnetos and igniter contacts, comprising an igniter-plug part for carrying the igniter contacts, a magneto-supporting part arranged to bear against the igniter-plug part, said two parts having registering bolt holes so that the same studs or bolts may be used for attaching both parts to the engine, said bolt holes being larger than the bolts or studs which they receive, and tubes fixed in the bolt holes of one part and projecting into the bolt holes of the other, to position the two parts relatively to each other, said tubes being of proper size to receive the attaching bolts or studs.

In witness whereof, I have hereunto set my hand at Indianapolis, Indiana, this 27th day of October, A. D. one thousand nine hundred and nineteen.

ARTHUR R. BAKER.
